METHOD OF AND APPARATUS FOR PACKAGING MATERIALS

Swan F. Anderson, Rockford, Ill.

Application March 2, 1936, Serial No. 66,624

20 Claims. (Cl. 226—99)

My invention relates to the packaging of liquid or semi-liquid materials discharged from a power driven forming or pressure producing mechanism and is especially adapted to the handling of such 5 materials as partially frozen ice cream delivered at a continuous rate of flow from what is commonly known as a continuous type freezing machine.

Ice cream as discharged from a freezer is a 10 partially frozen liquid containing a substantial portion of air by volume. It has been found that the foamy texture of the ice cream can best be preserved and a high quality maintained in the packaged product by maintaining the ice cream 15 under pressure and avoiding mechanical agitation thereof until it is discharged into the container in which it is to be handled.

An important object of the present invention is to provide a new and improved method of and 20 apparatus for conveying partially frozen ice cream directly from the freezer in which it is formed and for distributing measured quantities of the same automatically and periodically into containers which maintain the cream under 25 pressure up to the point of discharge into the containers. In carrying out this object, the ice cream discharged from a so-called continuous freezer is conveyed through a normally closed passage which is alternately opened and closed in 30 timed relation to the rate of delivery by the freezer and arranged to discharge measured quantities of the cream into successive containers.

Another object is to provide, in a combined 35 pressure-producing and packaging apparatus of the above character, a novel arrangement for preventing the valve from being opened except when a container is available to receive the discharged material and for preventing the material from being compressed to an objectionable degree while the discharge valve is held closed.

A more detailed object is to provide a packaging machine of the above character having a 40 normal discharge outlet and a by-pass outlet with valve means which is operated periodically either to open the first outlet when a container 45 is disposed in filling position or to open the by-pass outlet in the absence of a container.

The invention also resides in the novel character of the mechanism for actuating the multiple way valve.

Another object is to provide a novel mechanism 50 for interlocking the valve mechanism above referred to with the means by which the packaging machine is started so that the valve will be positioned to by-pass the material continuously when

the freezer or pressure-producing mechanism is operated with the packaging machine idle.

Another object is to provide a novel valve construction which permits the containers to be filled with a plurality of different kinds or flavors 5 of material such as partially frozen ice cream arranged in the container in vertically extending layers.

Further objects and advantages of my invention will become apparent as the following description proceeds and the features of novelty which characterize my invention are pointed out in particularity in the claims annexed to and forming a part of this specification.

For a better understanding of my invention 15 reference may be had to the accompanying drawings, in which

Figure 1 is a perspective view of a packaging machine embodying my invention.

Fig. 2 is a diagrammatic representation of a 20 continuous type, multiple unit, ice cream freezer for supplying partially frozen ice cream to the packaging machine shown in Fig. 1.

Fig. 3 is a fragmentary front elevation partly 25 in section along the line 3—3 in Fig. 4, and drawn on an enlarged scale, of the packaging machine shown in Fig. 1.

Fig. 4 is a fragmentary side elevation, partly 30 in section and drawn on an enlarged scale, of the packaging machine shown in Fig. 1.

Fig. 5 is an enlarged sectional view along the 35 line 5—5 of Fig. 4 of a portion of the automatic valve actuating mechanism of the packaging machine shown in Fig. 1.

Fig. 6 is an enlarged detail view of one of the 40 cams included in the valve actuating mechanism best shown in Fig. 4.

Fig. 7 is an enlarged sectional view along the 45 line 7—7 in Fig. 4 of the dispensing valve and its associated parts.

Fig. 8 is a sectional view along the line 8—8 of the valve mechanism shown in Fig. 7.

Fig. 9 is a sectional view along the line 9—9 of the valve mechanism shown in Fig. 7.

Fig. 10 is an enlarged front elevation in section 50 along the line 10—10 in Fig. 7 of a portion of the actuating mechanism for the dispensing valve shown in Fig. 7.

Referring to the drawings, I have shown in Fig. 1 a packaging machine embodying my invention 55 for periodically dispensing quantities of a material such as partially frozen ice cream supplied under pressure and in a continuous flow or stream by a freezer, such as that shown in Fig. 2, into a series of containers advanced successively into filling 55

position beneath an outlet of a valve controlling the flow from a closed conduit by which the ice cream is conveyed directly from the freezer to the filler. The valve is alternately opened and closed in timed relation to the movement of a conveyer by which the containers are advanced successively to filling position, the speed of the drive mechanism being adjustable so that valve-open and valve-closed intervals and therefore the quantity of cream discharged in each cycle may be varied as desired and the average rate of discharge synchronized with that of the freezer. Such intermittent closure of the valve and the consequent building up of the pressure to a valve such as to cause proper discharge of the cream when the valve is opened is made possible by virtue of the compressible character of the foamy ice cream. The conveyer conduit is also equipped with a second or by-pass outlet which is arranged to be opened automatically in each filler cycle in the event that there is no container in filling position at the time when the filler valve would normally be opened.

The freezer which is diagrammatically illustrated in Fig. 2 is of the so-called continuous type and of well known construction comprising a plurality of units 10, 11 and 12 for supplying ice cream of different flavors to the packaging machine. Each unit comprises a casing 13 supplied with a suitable refrigerating medium and houses a freezing chamber 14 into which the mixture of liquid ingredients and air are delivered by motor driven pumps 15 and 16. Motor driven stirring devices (not shown) within the chambers 13 operate in a well known way to advance the frozen mix to the freezer outlets from which the ice cream mixtures in semi-liquid form are discharged continuously and under pressure into conduits 17, 18 and 19 leading to the filling apparatus.

The packaging machine illustrated is of the same general type as that disclosed in my Patent No. 2,029,299 and comprises generally a mechanism 41 for dispensing cups 42 onto a traveling conveyer 43 by which the cups are presented to a filling mechanism 44, embodying certain aspects of my present invention, and are then carried to a mechanism 45 in which caps are applied to the filled cups. All of these mechanisms are mounted on a common frame having a suitable base 46 and are actuated by a main drive shaft 47 (Fig. 4) driven by an electric motor 48 through the medium of a speed control mechanism described in greater detail below and a pulley 49 mounted on the shaft 47.

The conveyer 43 comprises a series of spaced endless belts 50 extending about pulleys 51 and 52 which are driven from the main shaft 47 through the medium of shafts 53 and 54 and beveled gearing suitably connecting the shafts. At each operating station the successive cups 42 are elevated above the conveyer belts 50 and presented to the mechanism to operate thereon by platforms 55 mounted to slide vertically on the machine frame and having parallel upwardly opening grooves adapted to receive the conveyer belts 50 as the platforms are elevated to the position shown in Fig. 3. The platforms 55 for the different operating mechanisms are raised and lowered by cams 56 mounted on the shaft 54 and acting on the follower projections formed on the lower sides of the platforms 55. Other cams also carried by the shaft 54 behind cover plates 57 operate in proper timed relation to the filling mechanism to project stop fingers 58 above the con-

veyer belts 50 and thereby interrupt the movement of the cups 42 along the conveyer in proper positive timed relation to the filling mechanism 44.

Detailed description of the conveyer mechanism 43 as well as the cup dispensing mechanism 41 and capping mechanism 45 referred to above is unnecessary for a proper understanding of my present invention. It is sufficient here to say that during each revolution of the main operating shaft 47 a cup 42 is deposited on the conveyer belts 50 and also one of the cups 42 to be filled is raised and held in the filling position and is then filled with ice cream or the like from the dispensing mechanism 44, as is hereinafter described in greater detail. Then when the platform 55 is lowered, the filled cup is moved by the conveyer to the capping mechanism 45 and then onto a suitable receiving apron 59 from which it may be removed by an operator and placed in a carton or other shipping container.

The dispensing or filling apparatus 44 includes a three-way valve 60 of novel construction operated in synchronism with the cup presenting mechanism to close the conduits 17, 18 and 19 against the flow of ice cream therefrom or to establish communication between the conduits and nozzles directed toward a cup in filling position or to by-pass the ice cream. As best shown in Fig. 7, the valve comprises an outer cylindrical casing 61 having a cylindrical valve element 62 rotatably mounted in a bore 63 of the casing. Three segmental slots 64, 65 and 66 are formed in the side of the cylindrical valve element 62, and as best shown in Fig. 8, these slots cover substantially 180 degrees of the periphery of the valve element. The conduits 17, 18 and 19 supply partially frozen ice cream to the inlet connections or openings 67, 68 and 69 of the valve 60, which register with the slots 64, 65 and 66 respectively. The valve 60 is also provided with two discharge openings cooperating with each of the slots 64, 65 and 66 so that material supplied to the valve from the conduits 17, 18 and 19 may be alternatively directed to either of these sets of outlet openings or the valve may be entirely closed.

As best shown in Fig. 4, the lower discharge openings 70, 71 and 72, registering with the slots 64, 65 and 66 respectively, communicate with outlet openings 73, 74 and 75 formed in a filler outlet or filler nozzle 76 positioned below the valve 60 and adapted to direct ice cream into the cups 42 presented thereto. The discharge openings 73, 74 and 75 in the nozzle 76 are so arranged that the ice cream discharged into the cups 42 will be divided into three adjacent vertical layers in the cup as shown in Fig. 4.

The second set of outlet openings 77, 78 and 79 in the valve 60 communicate through conduits 80, 81 and 82 respectively with overflow receptacles 83, 84 and 85 respectively. The valve element 62 of the valve 60 may thus be rotated to the position shown in Fig. 8 in which the slots 64, 65 and 66 connect the inlet openings 67, 68 and 69 with the discharge openings 77, 78 and 79 in order to by-pass ice cream delivered from the freezers to the overflow receptacles 83, 84 and 85. Separate overflow receptacles are provided in order that the different flavors of ice cream will not be mixed.

An arrangement is provided for periodically actuating the valve 60 to move the member 62 to the filling position shown in Fig. 3 when a cup 42 is disposed beneath the outlet nozzle 76 and for then moving the member to closed posi-

tion, indicated in dotted lines in Fig. 3, when the cup has been filled. The valve 60 is then normally maintained in its closed position until the next cup is presented to the nozzle 76 when the valve is again opened. While the valve is closed, the pressure within the conduits 17, 18 and 19 builds up as permitted by compression of the air which the ice cream contains. The pressure developed is such that the cream may be discharged properly when the valve is again opened and this without the use of auxiliary pumping devices or the like which would relieve the pressure on the cream and tend to destroy its desired foamy texture. Thus, the partially frozen cream is maintained continuously under pressure which rises while the valve is closed and decreases while the valve is open. If for any reason a cup is not presented to the filler nozzle at the proper time in the operating cycle, the valve will be actuated to its by-pass position by an arrangement described below.

To oscillate the valve member 62 in this way, the actuating mechanism therefor includes a pinion 86 which is rotatably supported in a bore 86^a of a rear extension of the valve casing 61 and held against axial movement by engagement of shoulders 86^b with a flange on the forward end of the pinion and a flange 90 on a plug 90^a threading into a bore 89 in the pinion. The pinion is normally coupled to the valve member 62 by a key 87 guided in keyways 87^a in the pinion and urged by a compression spring 88 into a slot 93 in the rear end of the valve member. When the key is retracted axially to the position shown in Fig. 7, the pinion is disconnected from the valve member.

Upon an inspection of Fig. 7 it will also be noted that a pin 94 extends laterally from the end of the pinion 86 adjacent the valve element 62. This pin 94 is movable in a slot 95 formed in the adjacent end of the valve element 62 as best shown in Fig. 9. The pin 94 does not connect the pinion 86 and valve element 62 in driving relation but is simply provided in order to insure a proper re-assembly of the parts of the valve after it has been dis-assembled for purposes of cleaning and the like.

The pinion 86 is oscillated by an automatic actuating mechanism including vertically reciprocating racks 96 and 97 which mesh therewith and are mounted on opposite sides thereof on vertically extending rods 98 and 99 respectively. Thus, upon upward movement of the rack 97, the pinion 86 is rotated in a counterclockwise direction as viewed in Fig. 10, and the valve element 62 is moved from its closed position shown in dotted lines in Fig. 3 to its open position shown in full lines in Fig. 3. Then, upon downward movement of the rack 97, the pinion 86 is rotated in a clockwise direction so that the valve element 62 is moved back to its closed position. Alternatively, the valve element 62 may be moved in a clockwise direction from its closed position to its by-pass position shown in Fig. 8 upon upward movement of the rack 96, which causes a clockwise movement of the pinion 86 and valve element 62.

The rack 97 is normally reciprocated by a driving element including the main drive shaft 47 so that the valve 60 is periodically actuated from its open to its closed position in synchronism with the movement of the conveyer mechanism. The rack 96, which moves the valve 60 to its by-pass position, is also driven by an asso-

ciated driving mechanism including the main drive shaft 47.

The racks 96 and 97 are selectively rendered operative or inoperative in response to the presence or absence of a cup below the discharge nozzle 76 of the dispensing mechanism 44. Thus, if for any reason such as the exhaustion of the supply of cups, a cup is not presented to the discharge nozzle 76 at the proper time in the cycle of operation of the machine, the rack 97 is rendered inoperative and the rack 96 is rendered operative to move the valve to its by-pass position so that the ice cream supplied to the dispensing mechanism will be by-passed to the overflow receptacles 83, 84 and 85.

This selectively operable mechanism for the racks 96 and 97 includes a feeler arm 100, which is pivotally mounted on a pivot pin 101, and extends over the platform 55 below the dispensing nozzle 76. The feeler arm 100 cooperates with a vertical link 102 to form the arms of a linkage that is in effect a bell-crank having a lost motion connection between the arms thereof. This lost motion connection includes a tension spring 103, which is secured to the rearwardly extending end 25 of the feeler arm 100 and to the link 102 above the pivot pin 101. In addition the feeler arm 100 is provided with an upstanding arm 104 having a lip 105 which engages the rear edge of the link 102. Thus, when the feeler arm 100 is moved upwardly, on contact with one of the cups 42, it is rotated in a counterclockwise direction as viewed in Fig. 4 about the pivot pin 101. The spring 103 is thus placed under tension and swings the link 102 in a counterclockwise direction about the pivot 101. The spring 103 not only permits some relative motion between the feeler arm 100 and link 102 but also serves to bias the feeler arm 100 to its downward or depressed position.

When the cup 42 is moved downwardly on the platform 55 away from the feeler arm 100, the latter is permitted to move downwardly and the engagement of arm 104 with link 102 insures a positive return of the link 102 to its original position. The link 102 is provided with a slot 106 in the upper portion thereof through which a lateral extension 107 formed on the end of a horizontal link 108 extends, as best shown in Fig. 5. The link 108 is pivoted for movement about a vertical axis on a pin 109, which is in turn mounted on a bracket 110 extending forwardly from the front face of a vertically slidable bar or link 111.

The link 108 is alternatively movable into and out of engagement with the vertically extending rods 98 and 99 on which the racks 96 and 97 respectively are mounted. That is lock nuts 112 are threaded on the rod 98 above the link 108 and lock nuts 113 are threaded on the rod 99 above the link 108. Consequently when the link 108 is rotated about its pivot pin 109 in a clockwise direction as viewed in Fig. 5, the right-hand end thereof moves under the lock nuts 113 so that upon subsequent upward movement of the link 108 the rod 99 will be moved upwardly as will the rack 97 so that the pinion 86 will be rotated in a counterclockwise direction. Similarly, when the link 108 is oscillated in a counterclockwise direction as viewed in Fig. 5, the left-hand portion thereof will be moved under the lock nuts 112 and the right-hand end thereof will disengage lock nuts 113. Then upon subsequent upward movement of the link 108 the rod 98 will be moved upwardly as will the rack 96 and the pinion 86 will consequently be oscillated in a clockwise direction.

The necessary vertical reciprocatory movement is imparted to the link 108 by the vertically slidable link 111 to which it is secured by the bracket 110. The link 111 is in turn reciprocated by a positive driving mechanism which is hereinafter described. It will thus be seen that the movement of the feeler arm 100, in response to the presence or absence of a cup 42 below the dispensing nozzle 76, determines the movement of the valve rotor 62 either to its open or by-pass position.

Thus, when a cup 42 is moved into position below the dispensing nozzle 76, the feeler arm is moved upwardly and the link 102 is consequently moved rearwardly about the pivot 101. As a result, the link 108 is rotated in a clockwise direction as viewed from the top to the position shown in Fig. 5 in which the right-hand end thereof is positioned below the lock nuts 113. Then upon reciprocation of the link 108 by the link 111 the rod 99 is reciprocated thus moving the pinion 86 in a clockwise direction and turning the valve element 62 of the valve 60 from the dotted portion shown in Fig. 3 to the open portion shown in full lines in Fig. 3. If no cup is presented to the dispensing nozzle 76 the feeler arm 100 remains in its depressed position and the link 102 remains in its forward position holding the left-hand portion of the link 108 in engagement with the lock nuts 113 on rod 98. The vertical reciprocation of the link 108 by the link 111 causes the rod 98 and rack 96 to be vertically reciprocated. As a result, the pinion 86 is oscillated in a clockwise direction as viewed in Fig. 10 and the valve element 62 of the valve 60 is moved from the closed position shown in dotted lines in Fig. 3 to the by-pass position shown in Fig. 8. Thus, ice cream or other material supplied to the dispensing mechanism 44 is automatically by-passed to the over-flow receptacles 83, 84 and 85 whenever a cup is not positioned below the dispensing nozzle 76 for receiving the ice cream.

The link or plate 111 is slidably mounted for vertical reciprocation in guideways formed on the front of the vertical frame 114 and is reciprocated in a vertical direction by a cam 115 mounted on the shaft 53, which is in turn driven by the main drive shaft 47 through a suitable worm and gear connection, as best shown in Fig. 4. The cam 115, as shown in Fig. 6, is provided with a cam groove 116 in the front face thereof in which a follower 117 secured to the lower portion of the link 111 rides.

In view of this linkage mechanism used to operate the valve 60 from its open to its closed position, it will be seen that the valve 60 remains open during a predetermined and fixed portion of each revolution of the cam 115, which is indicated approximately by the arrow 118 in Fig. 6. Consequently, if it becomes necessary to increase or decrease the duration of the open period of the valve 60 in order that more or less ice cream or other material be discharged therefrom during each actuation thereof so as to fill the cups 42, it is necessary to change the speed of rotation of the cam 115. This change in speed of rotation of the cam 115 is accomplished by changing the speed of rotation of the main drive shaft 47 in the manner described below which also effects a corresponding change in the rate at which the cups 42 are advanced into filling position. Changes in speed of rotation of the drive shaft 47 not only vary the duration of the open periods of the valve 60 but also change the periodicity of operation thereof so that the total quantity of ice cream discharged thereby is consequently

varied and may thus be coordinated or synchronized with the rate of flow of ice cream from the freezers.

It will thus be seen that in the machine illustrated the ice cream is supplied, under pressure exerted thereon by the freezing machines, directly through conduits 17, 18 and 19 to the cups 42, the flow of ice cream being periodically interrupted by the dispensing valve 60. Thus the pressure exerted on the ice cream by the freezing machines is utilized to move the same through the filler or dispensing mechanism. In addition, the ice cream is maintained continuously under pressure in a closed conduit or conveying system so that the consistency and quality of the ice cream is preserved until discharged so that it closely approximates that of hand-packed ice cream.

In the machine illustrated, the speed regulation of the main drive shaft 47 is secured through the medium of a mechanical speed change device 20 comprising a conical disk 119 rigidly secured to the drive shaft 48a of the motor 48 and cooperating with a similarly shaped disk 120 to form a V-shaped drive pulley for a belt 121 extending around the pulley 49. The disk 120 is slidably mounted on the shaft 48a and is urged toward the disk 119 by a helical compression spring 122 so that by moving the motor shaft 48a toward and away from the axis of the pulley 49, the effective diameter of the drive pulley formed by the disks 119 and 120 may be increased and decreased progressively. To permit of such movement, the motor 48 is secured to a depending bracket 122a pivoted on a pin 123 adjacent the upper end thereof, the pin 123 being secured to the upper portion of the machine frame 46.

The position of the bracket 122a may be selectively adjusted in order to change the effective diameter of the pulley mounted on the motor shaft 48a by turning a screw shaft 124, which is threaded in a collar 125 secured to the bracket 122a. The screw shaft 124 is mounted in a collar 126 secured to the side of the machine frame 114, having a rotatable spline connection therewith which prevents axial movement of the screw shaft 124 in the collar 126. A manual operating handle 127 is secured to the forward end of the screw shaft 124 to facilitate adjustment thereof and effect the desired changes in driving speed of the main drive shaft 47. It will thus be seen that the operator of the machine may turn the hand-wheel to increase or decrease the speed of rotation of the drive shaft 47 which in turn varies the duration of the open period of the valve 60 as well as its periodicity of operation while at the same time maintaining the operation of the conveyer mechanism 43 in synchronism therewith. By means of this adjustable control the total amount of ice cream dispensed is made to equal that delivered by the freezers and each of the cups 42 is substantially filled.

Provision is made for insuring that the valve will be in by-passing position when the filler is idle so that the freezers may be in operation without danger of damaging the apparatus due to the development of excessive pressure. For this purpose, the filler is arranged to be started and stopped by operation of a manually operable lever 128 which also operates the valve 60. The lever is pivotally mounted on a rotatable end plate 129 held in position in the outer end of the cylindrical valve casing 61 by a locking collar 130. The locking collar 130 is, in turn, threaded on the outer end of the valve casing 61. The pivotal support for the operating lever 128 is formed by 75

a pivot pin 131 which extends between the arms of a yoke 132 formed on the front of the end plate 129. The pivot pin 131 is located eccentrically with respect to a rod 131^a extending 5 through the member 62 and abutting the key 87. The other end of the rod 131^a is thrust into engagement with the lever 128. The lower end of the manual operating lever 128 rides on a flange 133 formed on the outer edge of an arcuate supporting or guiding plate 134 which extends about 10 the lower front portion of a valve casing 61.

The manual operating lever 128 is movable to two extreme positions. In one of such positions, the lower end 128^a of the manual operating lever 15 rests in a notch 135 formed adjacent one end of the flange 133. In this position, the rod 131^a is moved forwardly by the spring 88 so that the key 92 engages the keyway 93 in the valve element 62 and the valve is operated by the automatic 20 actuating mechanism described above. In the other position of the manual operating lever 128, the lower end thereof rides outwardly on a projection 136 formed at the opposite end of the flange 133. When the lower end of the operating 25 lever 128 is thus moved outwardly by the projection 136, the rod 131^a is forced inwardly against the bias of the compression spring 88 so that the key 92 disengages the keyway 93 and the pinion 86 of the automatic valve actuating mechanism 30 is no longer connected to the valve element 62.

Rearward movement of the key 88 also moves a switch arm or bridging member 137 away from fixed contacts 138. The bridging member 137 and fixed contacts 138 constitute a deenergizing switch connected in the energizing circuit of the motor 48 so that the motor is consequently deenergized upon the movement of the bridging member 137 to switch-open position and simultaneously moves the valve member to by-pass 35 position by swinging the handle 128 in a clockwise direction as viewed in Fig. 1, causing a clockwise movement of the end plate 129. The end plate 129 is provided with an inwardly extending shoulder 139 (Figs. 7 and 9) which engages a complementary shoulder 140 formed on the front end of the valve element 62. The engagement of the shoulder 139 with the shoulder 140 causes the valve element 62 to be rotated in a clockwise 40 direction, as viewed from the front end thereof, to the by-pass position shown in Fig. 8. It should be noted that the projection on the inner face of the end plate 129 forming the shoulder 139 is sufficiently short in arcuate length that the valve element 62 is free to oscillate during 45 the normal automatic actuation thereof without interference from the shoulder 139. This relation of the shoulders 139 and 140 can best be seen from an inspection of Fig. 9. It will thus be seen that the manual control handle 128 may be utilized to simultaneously disconnect the automatic 50 actuating mechanism from the valve 60, deenergize the main driving motor 48, and move the valve 60 to its by-pass position. Such a manually operable supervisory control arrangement 55 greatly increases the safety of operation of the machine since it may be quickly stopped and any ice cream subsequently supplied thereto by continued operation of the freezers is bypassed to the overflow receptacles. Likewise, in filling a batch of containers, the freezers may be started and adjusted to give the desired rate of flow before the filler is started.

It may be desirable under some conditions to 70 operate the filler with the valve member 62

positioned to maintain the filler nozzle outlets open continuously. This may be accomplished by starting the motor and then pressing inwardly on the operating handle 128 when the valve member 62 is in the normal open position. The valve member thus becomes uncoupled from the pinion 86 and remains in open position so long as the handle 128 is held inwardly by engagement with the flange 133 at a point adjacent the notch 135 as shown in dotted outline in Fig. 7. 10

The construction of the valve 60 and operating mechanism therefor described above is particularly advantageous in that it may be readily disassembled and reassembled in order to facilitate frequent cleaning of the same. Thus, in 15 disassembling the valve, the end plate 129 and the lever 128 are removed by unscrewing the collar 130. The valve element 62 and the rod 131^a may then be readily removed from the valve casing 61. After the valve 60 has been so disassembled, it may be thoroughly cleaned with steam 20 or hot water and the entire system of conduits through which the ice cream passes may be similarly flushed out and cleaned.

Although I have shown and described in detail a particular embodiment of my invention in order to facilitate a proper understanding thereof I do not desire my invention to be limited to the particular construction shown and described and I intend in the appended claims to cover all 30 modifications within the spirit and scope of my invention. 25

I claim as my invention:

1. In combination with a machine for delivering a liquid under pressure in a continuous flow, 35 filling means including a valve movable to open and closed positions for periodically interrupting the flow of liquid delivered thereto under pressure exerted on the liquid by said machine, conveying means for presenting successive containers to 40 said filling means, power driving means for periodically actuating said valve to its open and closed positions, and means for selectively varying the speed of said driving means to vary the duration of the open periods of said valve and 45 thereby vary the quantity of material discharged under the pressure exerted thereon by said machine.

2. In combination with a machine for delivering a liquid under pressure in a continuous flow, 50 filling means including a valve movable to open and closed positions for periodically interrupting the flow of liquid delivered thereto under pressure exerted on the liquid by said machine, conveying means for presenting containers successively to 55 said filling means, common driving means for periodically opening and closing said valve and for actuating said conveying means, and means for selectively varying the speed of said common driving means to vary the duration of the open 60 periods of said valve and thereby coordinate the quantity of material discharged under the pressure exerted thereon by said machine into said containers with the quantity of material delivered from said machine. 65

3. In combination with a machine for delivering a continuous stream of liquid, filling means for periodically discharging quantities of the liquid delivered from the machine to successive containers upon successive actuations of said filling 70 means, conveying means for presenting successive containers to said filling means, and means for varying the quantity of material discharged by said filling means during each of the successive actuations thereof and for selectively varying the 75

periodicity of the actuations of said filling means.

4. In combination with a machine for delivering liquid in a continuous flow, means including a valve having two discharge openings for dispensing liquid delivered from said machine, said valve having a normal position in which said openings are both closed and two positions in which the respective openings are opened, one of said discharge openings communicating

10 through a filler outlet with successive containers for the liquid, conveying means for presenting successive containers to said one opening, driving means for periodically moving said valve member out of said normal position and into a

15 position to open said one opening, means for varying the speed of said driving means to vary the duration of the open periods of said valve, and means controlled by successive containers presented by said conveying means to said filler outlet for actuating said valve member to close said one opening and open said other opening when no container is presented for filling.

5. In combination with a machine for delivering liquid in a continuous flow, means including

25 a valve having two discharge openings for dispensing liquid delivered from said machine, one of said discharge openings communicating through a filler outlet with successive containers for the liquid, conveying means for presenting

30 successive containers to said one opening, said valve including a rotatable valve element for controlling said openings, a pinion operatively connected to said rotatable valve element, a recipro

35 cipable rack meshing with said pinion, driv

ing means for reciprocating said rack to periodically oscillate said valve element to open and close

39 said one opening, and means controlled by successive containers presented by said conveying

40 means to said filler outlet for disconnecting said rack from said driving means and for actuating said valve to close said one opening and open said other opening when no container is presented for filling.

6. In combination with a machine for delivering

45 liquid in a continuous flow, means including a valve receiving liquid under pressure from said machine and having two discharge openings for dispensing liquid delivered from said machine, one of said discharge openings communicating

50 through a filler outlet with containers successively presented thereto, said other opening communicating with an overflow receptacle, said

55 valve including a rotatable valve element for controlling said openings, a pinion operatively connected to said rotatable valve element, means

60 including a recipro

65 cipable rack meshing with said pinion for periodically oscillating said valve element to open and close said one opening while maintaining said other opening closed, means

70 including a second rack meshing with said pinion for periodically oscillating said valve element to open and close said other opening while maintaining said one opening closed, driving means for reciprocating said racks, and means controlled by the presence or absence of containers

75 opposite said filler outlet for alternatively connecting said racks to said driving means.

7. In combination with a machine for delivering liquid in a continuous flow, means includ

70 ing a valve receiving liquid under pressure from said machine and having two discharge openings for dispensing liquid delivered from said machine, one of said discharge openings communicating through a filler outlet with containers suc

75 cessively presented thereto, said valve including

a rotatable valve element for controlling said filler opening, a pinion operatively connected to said rotatable valve element, means including a recipro

8 cipable rack meshing with said pinion for periodically oscillating said valve element to open and close said filler opening while maintaining

85 said other opening closed, means including a second rack meshing with said pinion for periodically oscillating said valve element to open and close said other opening while maintaining said

90 filler opening closed, driving means for reciprocating said racks, and means including a feeler arm arranged to contact with containers presented to said filler outlet for connecting said

95 racks selectively to said driving means.

8. In combination with a machine for delivering liquid in a continuous flow, means including a valve receiving liquid from said machine and having a movable member and two discharge openings for dispensing liquid delivered from said ma

10 chine, one of said discharge openings communicat

15 ing through a filler outlet with successive containers for the liquid, driving means for periodically moving said member from a position closing both of said openings to a position in which

18 said filler opening is opened, means for varying

20 the speed of said driving means to vary the duration of the open periods of said valve, and means

25 including a feeler arm arranged to contact containers presented to said filler outlets for moving

30 said valve member from said first position to a position opening said other opening when no con

35 tainer is presented for filling.

9. In combination with a machine for deliver

35 ing a liquid in a continuous flow, filling means in

cluding a valve for receiving said liquid and peri

odically discharging quantities thereof into suc

cessive containers, means for presenting suc

cessive containers to said filling means, driving

40 means for periodically actuating said valve to

45 its open and closed positions, means for varying

48 the speed of said driving means to vary the peri

50 odicity of operation of said valve and simultane

55 ously to vary the speed of said container present

58 ing means, and means controlled by successive

61 containers presented by said conveying means

64 to said filling means to by-pass liquid to an over

68 flow receptacle during the normal valve open

72 period when no receptacle is presented to said fill

76 ing means.

10. In combination with a machine for deliver

50 ing a liquid in a continuous flow, filling means in

cluding a valve for periodically discharging

55 quantities of the liquid delivered from said ma

chine directly into successive containers presented

60 to the filling means, driving means for periodi

65 cally actuating said valve to its open and closed

70 positions, control means for varying the speed

75 of said driving means to vary the periodicity of

80 operation of said valve, means controlled by suc

85 cessive containers presented to said filling means

88 for by-passing liquid around said valve when no

92 receptacle is presented to said filling means, and

96 manually operable supervisory control means for

98 by-passing the liquid to an overflow receptacle

100 irrespective of the operation of said first named

control means.

11. In combination with a machine for deliver

70 ing a liquid in a continuous flow, filling means in

cluding a valve for periodically discharging

75 quantities of the liquid delivered from said ma

chine directly into successive containers presented

80 to said filling means, driving means including

85 an electric driving motor for periodically actu

90 ating said valve to its open and closed positions,

95 means controlled by successive containers pre

100

5 sents to said filling means for by-passing liquid to an overflow receptacle when no receptacle is presented to said filling means, and manually operable supervisory control means for by-passing the liquid to an overflow receptacle irrespective of the operation of said first named control means and for deenergizing said electric driving motor.

10 12. The combination of a closed chamber having a filler outlet, a by-pass outlet, valve means controlling the flow of material through the respective outlets, a machine for delivering liquid material under pressure in a continuous flow to said chamber, a common operating member for said valve means having a first position in which said filler outlet is open, a second position in which both of said outlets are closed, and a third position in which said by-pass outlet is open, a continuously reciprocated actuating element operable upon movement in one direction to move said member to valve-closed position, two separate drive connections between said element and said member one adapted to move the member to said first position and the other to move the member to said third position, and means responsive to the presence or absence of a container to be filled opposite said filler outlet to selectively establish one or the other of said connections.

15 13. The combination of a closed chamber having a filler outlet, a by-pass outlet, valve means controlling the flow of material through the respective outlets, a machine for delivering liquid material under pressure and in a continuous flow to said chamber, mechanically actuated means operating periodically to actuate said valve means to open one or the other of said outlets and then close the outlet, power driving means for actuating said last mentioned means, and a common control member governing the starting and stopping of said power driven means and opening and closing of the second outlet.

20 14. The combination of a closed chamber having a filler outlet, a by-pass outlet valve means controlling said outlets, a power driven machine for delivering liquid material under pressure and in a continuous flow to said chamber, a mechanically reciprocated member having separate drive connections for actuating said valve means to open one or the other of said outlets on one of its strokes, and means selectively responsive to the presence or absence of a container opposite said filler outlet to render one or the other of said connections operative.

25 15. The combination of a closed chamber having a filler outlet, a by-pass outlet, valve means controlling said outlets, a power driven machine for delivering liquid material under pressure and in a continuous flow to said chamber, an oscillatable member selectively operable to actuate said valve means to open one or the other of said outlets in one of its strokes, and means by which the rate of oscillation of said member may be varied.

30 16. The combination of a plurality of closed chambers having separate discharge outlets, a common filler outlet, separate by-pass outlets from the respective chambers, a common valve

35 member movable to a first position establishing communication between said chambers and said filler outlet, a second position in which the outlets from said chambers are closed, and a third position in which the chambers are connected to said discharge outlets, and a common power actuated means for periodically moving said member to said second position and alternately moving the member selectively to said first or third positions.

40 17. The method of forming and packaging ice cream which consists in forming semi-fluid ice cream in a continuous flow and under pressure as an incident to the formation thereof, maintaining the ice cream continuously under pressure between the point of formation and the point of discharge by delivering the same directly to a discharge orifice through a closed conduit, periodically and alternately opening and closing said orifice to alternately increase and decrease the pressure under which the material is placed, and equalizing the average rate of discharge and the rate of delivery of the ice cream.

45 18. The method of packaging liquid material which consists in delivering the material under pressure and in a continuous flow to a discharge orifice through a closed conduit, periodically and alternately opening and closing said orifice, and adjusting the periodicity of the open and closed periods to equalize the average rate of material discharged from said orifice and the rate of delivery.

50 19. The method of forming and packaging ice cream which consists in forming semi-fluid ice cream in a continuous flow and under pressure as an incident to the formation thereof, maintaining the ice cream continuously under pressure between the point of formation and the point of discharge by delivering the same directly to a discharge orifice through a closed conduit, and alternately opening and closing said orifice in timed relation to the rate of formation whereby the average rate of intermittent discharge equals said rate of formation.

55 20. The combination with a device for forming and delivering semi-liquid ice cream in a continuous stream and under superatmospheric pressure exerted thereon as an incident to the formation thereof, of dispensing means including a valve controlled dispensing orifice for utilizing the pressure exerted on the stream by said device incident to the formation thereof for expelling the material through said orifice in segregated rapidly flowing batches without the interposition of an intermediate discharge pressure producing device, said last named means including a power actuated mechanism for periodically opening said valve and alternately closing the same for sufficiently long closed periods to enable the ice cream in the stream to be placed under sufficient pressure to effect ready expulsion thereof when the valve is opened, and means by which the valve-open and valve-closed periods may be selectively varied to establish an average rate of discharge corresponding to the rate of delivery.
